UNITED STATES PATENT OFFICE

169,122

VASE OR SIMILAR ARTICLE

Ray D. Butler, Miami, Fla.

Application November 5, 1952, Serial No. 22,139

Term of patent 7 years

(Cl. D29—28)

To all whom it may concern:

Be it known that I, Ray D. Butler, a citizen of the United States, residing at Miami, county of Dade, and State of Florida, have invented a new, original, and ornamental Design for a Vase or Similar Article, of which the following is a specification, reference being had to the accompanying drawing, forming a part thereof.

Figure 1 is a side elevational view of a vase or similar article, showing my new design,

I claim:

The ornamental design for a vase or similar article, as shown.

RAY D. BUTLER.
